UNITED STATES PATENT OFFICE.

WILLIAM R. CAMPBELL, OF LANCASTER, OHIO.

GLASS-DRAWING APPARATUS.

1,122,476.

Specification of Letters Patent. Patented Dec. 29, 1914.

Application filed September 27, 1913. Serial No. 792,150.

To all whom it may concern:

Be it known that I, WILLIAM R. CAMPBELL, of Lancaster, in the county of Fairfield and State of Ohio, have invented certain new and useful Improvements in Glass-Drawing Apparatus; and I do hereby declare the following to be a full, clear, and exact description of the invention, such as will enable others skilled in the art to which it appertains to make and use the same.

My invention relates to an improvement in glass drawing apparatus, and it consists in a stationary heating furnace, and a frame having pot carrying supports at right angles to each other, the said frame being mounted to rock through an arc of ninety degrees whereby one pot support will be shifted from a horizontal to a vertical position and the other shifted from a vertical to a horizontal position and a turn table on which said frame is mounted, whereby the frame may be turned so as to support either pot adjacent and parallel to the furnace so as to be heated by the latter, while the cylinder is being drawn from the glass in the pot on the horizontal table.

My invention further consists in a furnace and a rocking frame mounted on a turn-table and carrying two pots located end to end and at right angles, so that a quarter turn of the frame will lower one pot to a vertical position and raise the other to a horizontal position, and a half turn of the turn table will reverse the position of the rocking frame relative to the furnace whereby both pots may be moved to position to be heated by the furnace.

My invention further consists in the details of construction as will be more fully explained and pointed out in the claims.

In the accompanying drawings, Figure 1 is a view in elevation of an apparatus embodying my invention and Fig. 2 is a similar view of a modification of the same.

1 represents a circular track, and 2 is a turn table mounted on flanged wheels 3, which latter rest on the track.

4 is a frame secured to the turn table and provided with bearings 5, in which the shaft 6 has a rocking movement. Rigidly secured to the shaft 6, are the arms 7 which carry the pot supporting tables 8. These two tables are located edge to edge and at right angles as shown, and each carries a pot 9, the construction being such that when one pot is in its horizontal position, which is its

position when the glass is being drawn therefrom, the other will be in a vertical or drawing position, thus permitting the excess of glass to drain therefrom prior to its being turned to a horizontal position. A quarter turn of the shaft 6 shifts the vertical pot 9 into a horizontal position, and the horizontal pot into a vertical position, and a half turn of the turn table 2, carries the vertical pot 65 around one hundred and eighty degrees.

Secured to the shaft 6, is the worm gear 10, which is in mesh with the worm 11 on the armature shaft 12 of the motor 13. The conductor wires 14 leading to the motor are 70 connected with a reversing switch member 15, carried by the turn-table 2 and which is constructed to make contact with a switch member 16 located at the side of the turn table. Upon starting the motor, the worm 75 11, acting on worm gear 10, turns the shaft 6 and thus turns the frame 7 in a direction to carry the vertical table to a horizontal position and the horizontal table to a vertical position, the construction being such 80 that the motor may be reversed, which is essential with the pot supports as herein shown.

Secured to the turn table 2 at its center, is the shaft 17, which is supported near its 85 lower end in a bearing 18, and is provided at its lower end with a bevel gear 19, which meshes with a bevel pinion 20 on the armature shaft 21 of the motor 22. By energizing this motor, the turn table may be turned 90 on its trackway 1, and carry with it the rocking frame carrying the two pots 9.

23 is a furnace preferably provided with a concave inner face, and with fuel burners 24 which may be for oil or gas, the openings 95 25 through which the burner pipes pass, being larger than the burner pipes, so as to permit the free passage of air, which commingling with the oil or gas as the latter issues from the burner, produces an intense 100 heat sufficient to melt the excess glass remaining in the pot. This furnace is so located relative to the pots carrying frame that the vertical pot will rest close up to the furnace, and the glass remaining therein 105 will be melted, and as it becomes fluid, drain from the pot thus leaving the latter clean and ready to receive another supply of melted glass.

In the operation of the apparatus the 110 horizontal pot is under the drawing apparatus and contains the supply of melted

2

glass from which the cylinder is drawn, the other pot being in position adjacent the furnace so as to be heated thereby, and its excess glass melted and permitted to drain off.

5 After the cylinder has been drawn from the horizontal pot, the frame carrying the pots is rocked through an arc of ninety degrees, and the turn table given a half turn, so as to bring the pot from which the cylinder was drawn into a position before the furnace.

10 The sequence in which these acts occur is not important. The frame may first be rocked to change the position of the pots, after which the turn table may be turned to carry the vertical pot around to the furnace, but I prefer to first actuate the turn table so as to carry the vertical pot away from the furnace and then rock the pots carrying frame, so that as the horizontal

15 pot descends to a vertical position, all fluid glass therein will drain off into the pit immediately in front of the furnace.

20 The construction shown in Fig. 2 is identical with that shown in Fig. 1, except as to the gearing for actuating the rocking frame and turn table. In Fig. 2 shaft 26 passes loosely through the turn table 2, and is provided at its lower end with a bevel gear 27 which meshes with the bevel gear 28 on the

25 armature shaft 29 of the motor 30. The upper end of shaft 26 is provided with a gear 31 which meshes with a gear 32 on horizontal shaft 33. This shaft is journaled in a bearing 34 secured to the frame 4, and is provided at its opposite end with a gear 35 meshing with gear 36 fast on shaft 6.

30 With the construction shown, the rocking frame carrying the pots can only rock through a quarter circle, hence with the

35 construction shown in Fig. 2, if power be applied from motor 30 to shaft 26, in a direction to carry the vertical table downwardly, the shaft 35 cannot rotate, consequently the rotation of shaft 26, will operate

40 through the locked shaft 35 to rotate the turn table and the parts thereon, and thus carry the vertical pot away from the furnace. If now the motor 30 be reversed, shaft 33 will be rotated in a direction to turn

45 gear 36 and rock the pots carrying frame a quarter turn, thus carrying the vertical pot which has been heated and drained to a horizontal position, and the other pot to a vertical position in front of the furnace.

50 It is of course evident that the shaft 26 may be first rotated in a direction to rock the pots carrying frame, and after the latter has made a quarter turn, it will become

55 blocked against further movement, and a continued rotation in the same direction,

60 will operate to turn the table 2 and the parts thereon. It is also evident that other changes in the construction and relative arrangement of parts may be resorted to without departing from the spirit of my invention.

tion, hence I would have it understood that I do not confine myself to the exact construction shown but consider myself at liberty to make such changes as may come within the scope of my invention.

Having fully described my invention what I claim as new and desire to secure by Letters-Patent, is:—

1. In glass drawing apparatus, the combination of a stationary furnace constructed to heat a pot when the latter is in a vertical position in front of the furnace, a horizontal turn table adjacent to the furnace, and a rocking frame on said turn table and provided with two pot supports at right angles to each other whereby either pot support may be turned to carry its pot to a position in front of the furnace so as to be heated thereby.

2. In glass drawing apparatus, the combination of a vertical furnace, a horizontal turn table located in front of and adjacent to said furnace, a frame on said turn table and adapted to rock through an arc of ninety degrees, pot supports carried by said frame, the said supports being at right angles to each other and means for rocking said frame.

3. In glass drawing apparatus, the combination of a vertical furnace, a horizontal turn table located in front of and adjacent to the furnace, a rocking frame carried by said turn table and a plurality of pot supporting tables carried by said frame, the construction being such that any one of the tables may be turned to present its pot to the furnace so as to be heated thereby.

4. In glass drawing apparatus, the combination of a furnace, a turn table at the front of and adjacent to the furnace, a pivoted frame on said turn table, a series of pot supports on said frame and a pot on each support, the construction being such that any one of the pots may be turned from a horizontal position to a vertical position in front of the furnace so as to be heated thereby.

5. In glass drawing apparatus, the combination of a furnace, a turn table located in front of and adjacent to the furnace, a rocking frame on said turn table, two tables on said frame, the tables being edge to edge and at right angles to each other, a pot on each table, means for rocking the frame to move one pot from a horizontal to a vertical position and the other pot from a vertical to a horizontal position, and means for rotating the turn table whereby either pot may be moved to a position in front of the furnace.

6. In glass drawing apparatus, the combination of a vertical furnace, a horizontal turn table located in front of and adjacent to the furnace, a rocking frame on said turn table, two pot carrying tables on the

frame, the pot carrying tables being at right angles to each other, a pot on each table, a motor and gearing for actuating the turn table and an independent motor and gearing carried by the turn table for actuating the rocking frame.

In testimony whereof, I have signed this

specification in the presence of two subscribing witnesses.

WILLIAM R. CAMPBELL.
